UNITED STATES PATENT OFFICE

FRED NICHOLAS NELSON, OF SEATTLE, WASHINGTON, ASSIGNOR TO SAFETY BOAT CO.,
OF SEATTLE, WASHINGTON, A CORPORATION OF WASHINGTON

VENTILATOR

Application filed January 4, 1930, Serial No. 418,581, and in Great Britain January 1, 1929.

This invention relates to ventilators, and more particularly, but not exclusively, to ventilators for ships and boats and has for its chief object the provision of ventilators that can function efficiently at all times, including stormy weather, when ordinary ventilators are useless in the event of waves or spray breaking over the ship or boat, and also to provide means of protection against poison gas, the accumulation of fumes, control in case of fire, fumigation, refrigeration, capsizing and the like, and which ventilators may also be modified to make use of the structure of the vessel as part or parts thereof.

According to this invention, the improved ventilator comprises a primary trunk having a cowl at the upper end thereof and an automatic clearing port or ports and a closing device or devices therefor at the lower end of the trunk, an opening or openings in the primary trunk leading to the space or spaces to be ventilated, a device located above the said opening or openings to deflect any water entering the primary trunk, and a float valve or valves adapted to close the said opening or openings.

Other features of the invention are herein-after set forth in the claims.

In order that the said invention may be clearly understood and readily carried into effect, the same will now be described more fully, by way of example, with reference to the accompanying drawings, in which:—

Figure 1 is a vertical sectional view of a ventilator embodying the invention;

Figure 2 is a vertical sectional view taken at right angles to Figure 1;

Figure 3 is a cross section taken on the line $\alpha-\alpha$, Figure 1;

Figure 4 is a vertical sectional detail view, on an enlarged scale, showing means for operating a cover for closing the opening leading from the primary trunk into the space or spaces to be ventilated;

Figure 5 is a fragmentary vertical section showing a modification, and

Figure 6 is an elevation taken at right angles to Figure 5.

Referring more particularly to Figures 1

to 4 of the accompanying drawings, 1 designates the primary trunk, 2 the cowl of the preferred construction, the cowl being rotatable, 3 the deck at the end of what may be a forecastle, bridge, poop deck, or any superstructure of a vessel, 4 the bulkhead thereof, 5 the clearing port, 6 the closing device for the said clearing port, 7 the opening leading from the primary trunk into the space to be ventilated, 8 the watershed or deflector above the opening, and 9 the float valve, normally at rest on an angle bar 10, but always to serve as a closure for the opening 7, when required.

Guide rods 11 are secured to the ends of the angle bar 10 and by lugs 12 to the bulkhead 4 and co-operate with lugs 13 attached to the float valve to guide the float, as hereinafter described.

When it is desired to conduct the air current to or from a space beyond the space for which the opening 7 forms an inlet or outlet, a secondary trunk or trunks 14 is or are provided, from which trunk or trunks air ducts may be led to individual compartments.

Around the opening 7 a frame 15 is fitted, having attached thereto a gasket 16 secured in place by binding strips 17. On the opposite side of the opening 7 provision is made for fitting a suitable cover 18, in order to close the said opening in case of emergency, which cover, when there is no secondary trunk, may be of the type ordinarily used in ships, but which, when enclosed by a secondary trunk, requires to be operable from the outside, in some convenient place and is here shown connected by jointed links 19 and 20 to a screw threaded shaft 21, passing through the deck 3 and a correspondingly threaded bearing 22 on top of the deck, the shaft 21 having fitted at the outer end thereof a wheel 23, or a handle, by which the shaft can be turned so as to operate the cover 18 and move it into open or closed position. The link 20 has a pin-and-slot connection with a bracket 24 secured to the secondary trunk. When the cover is lowered and the links 19 and 20 are in a substantially horizontal position, the cover is forced tightly against the frame 15, the end 20' of the link 20 abutting against the secondary trunk, which is suit-

ably stiffened. Where the cover is of excessive size, or excessive pressure is likely to be encountered, a suitable arrangement of clamps and dogs would be provided to meet the requirements.

5 The guide rods 11 for the float valve are formed so as to permit the valve to travel freely thereon until about reaching the upper limit of the opening 7, whereupon the valve, 10 through the intervention of the lugs co-operating with off-sets 25 of the guide rods, is caused to engage with and compress the gasket 16 to effect a tight joint, as indicated by dotted lines in Figure 1. The float valve 15 may be of any suitable formation and the engaging face may be made straight, as shown, or curved to correspond with the shape of the trunk or bulkhead with which the float makes contact. The float valve is arranged 20 to operate automatically as a closure against water or any other liquid entering the opening 7, but is also provided with means to control the same mechanically (without interfering with the automatic action thereof, unless it is completely closed) so that the float 25 will serve a number of other purposes, such as those previously stated.

The particular means shown for mechanically controlling the float valve comprises a 30 rod 26, passing through the horizontal flange of the angle bar 10, the said flange being offset at 26' to accommodate a pad 27 at the upper end of the rod 26. The said rod is guided between a bracket 28 and a flanged plate 29 secured thereto, the bracket being secured to the bulkhead 4 and also serving as a stop at 35 28' for the device 6 which automatically closes the clearing port 5. The rod 26 is operated, in the example shown, by means of a flexible cord 30, secured at 31 to the said rod and passing over a pulley 32, through an opening in the side of the primary trunk, over a second pulley 32' to a cleat or the like 40 exterior of the trunk.

45 In the event of the ventilator being submerged in an inverted position (for instance in small vessels or boats that may be righted again) means are provided for using the float as a closure in such a contingency. For 50 purposes of illustration, the means provided comprise a counterweight 33 secured to the rod 26, the combined weight of the said rod and counterweight being sufficient to overcome the buoyancy of the float and cause it to 55 close the opening 7.

60 The mechanical control of the float valve (local control or remote or "master" control, or both) may be accomplished by any appropriate means, such as a solenoid or other electrical device, or counterweights, push or pull rods or wires, telemotors, compressed air, steam, or any desired means for the purpose.

65 The closing device 6, for the clearing port 5, is shown pivotally mounted at the lower end of the primary trunk in such a manner

as normally to remain closed by its own weight, with sufficient force to trap the air in the trunk but capable of opening automatically, when water accumulates in the said trunk, to close automatically when the water is discharged and to remain closed against the entrance of water from the exterior.

70 The closing element is so mounted as to normally remain closed by gravity and, as will be apparent from Figure 1 of the drawings, the area of the element below the pivot is somewhat larger than the area above the pivot. This tends to hold the element closed under external pressure of water by reason of the pressure exerted on the lower and larger pressure area overcoming the same pressure on the upper and smaller pressure area, which would otherwise tend to open the element. Of course, under these conditions 75 an accumulation of water within the trunk will tend to open the closing element, it, of course, being the intention to so balance the element to gain the advantages noted and to cause the element to open under the accumulating weight of water in the trunk, while failing to respond in a similar manner to any weight of air which might be accumulated in the trunk. That is to say, the weight of water will open the element and 80 automatically clear the trunk, while the weight of the contained air is insufficient to open the element.

85 The closing device, or each closing device, may be of the nature of a water trap, a partially balanced butterfly valve, a weight or spring controlled non-return valve, a swinging freeing port, or a device of any other character suitable for the purpose.

90 The modification shown in Figures 5 and 6 is substantially the same as that above described with reference to Figures 1 to 4 of the drawing, except that there is provided a cowl 2' which is permanently fixed.

95 Without defining the limits of the invention, a ventilator according to the present invention may be located, for example, at the end (forward or aft) of a ship's bridge or deckhouse, or at the end of the forecastle or poop deck, with the supply cowl or inlet 100 facing forward, and the exhaust cowl or outlet facing aft, with either fixed or rotatable cowls, to suit conditions. When the ship moves ahead or faces the wind, air will be forced and slightly compressed into the primary trunk. The closing device at the bottom of the trunk will prevent the escape of the air by way of the clearing port or ports and the air will be forced into and through the air trunk or trunks, ducts or leads into and through the compartments or spaces to be ventilated and out through a similarly 105 constructed exhaust trunk, cowl or outlet. Rain, spray, drift or waves that would make it necessary to turn away or to close the or- 110

dinary kind of ventilators, do not prevent the effective operation of a ventilator according to the present invention, for the water is deflected into the bottom of the primary trunk by the sides of the trunk and the deflector and is cleared away by the automatic clearing ports, without danger of water entering the air trunks, ducts or leads. However, in extremely stormy weather it 5 may happen that the crest of a wave may rise so high above the ship as temporarily to fill the whole ventilator, and to provide against entrance of water into the air trunks, ducts or leads and through them into the 10 compartments or spaces to be ventilated, the float valves are provided, while they also serve other purposes, as above described. If, then, water rises in the primary trunk high enough so that there is danger of water entering the air trunks, the buoyant float will be raised by the water so as temporarily to close the opening and, when the crest of the wave has passed (the submersion being 15 for an instant only) the clearing port immediately emits the water out of the primary trunk, and, as the water recedes, the float immediately drops and permits air to pass through the spaces to be ventilated, leaving them freely ventilated, yet water- 20 tight.

By a proper arrangement of the trunks, ducts and leads, this method of ventilation can be made to scavenge out accumulations of petrol or other explosive or poisonous 25 fumes and gases, whether heavier or lighter than air, and the ventilator itself is ready for the various uses previously described. The whole system or any part thereof, may also be used either for natural ventilation 30 or connected with blowers and fans for forced ventilation, when desired.

What I claim is:—

1. A ventilator comprising a primary trunk having a cowl at the upper end thereof 45 and an automatic clearing port or ports and closing device or devices therefor at the lower end of the trunk, an opening or openings in the primary trunk leading to the space or spaces to be ventilated, a device located above 50 the said opening or openings to shed any water entering the primary trunk, and a float valve or valves adapted to close the said opening or openings.

2. A ventilator according to claim 1, having associated therewith a secondary trunk 55 adapted to serve as an air duct.

3. A ventilator according to claim 1, in which the structure of a vessel forms part 60 of the ventilator.

4. A ventilator according to claim 1, having means for mechanically controlling the 65 float valve or valves.

5. A ventilator according to claim 1 in which the opening or each opening leading 70 from the primary trunk is provided with a

controllable cover adapted to close the same in case of emergency.

6. A ventilator according to claim 1, in which the float valve or each float valve is guided by rods or the like, the valve or each valve having lugs or the like adapted to co-operate with offsets of the said rods or the like to compress a gasket or other sealing means to effect a tight joint around the opening or corresponding opening leading from the primary trunk. 70

7. A ventilator according to claim 1, having means for controlling the float valve or valves, the said means comprising a guided rod adapted to be operated by means of a flexible cord or the like operable exteriorly of the ventilator. 75

8. A ventilator according to claim 1, in which means are provided to ensure that the float valve or valves will close the opening or openings leading from the primary trunk in the event of the ventilator being submerged in an inverted position. 80

9. A ventilator comprising a primary trunk open at the upper end, an automatic trunk-clearing element at the lower end, a ventilating opening in the trunk between the upper open end and the automatic trunk clearing opening, and means for automatically closing said opening incident to the accumulation of water in the trunk. 85

10. A ventilator comprising a primary trunk open at the upper end, an automatic trunk-clearing element at the lower end, a ventilating opening in the trunk between the upper open end and the automatic trunk clearing opening, means responsive to the accumulation of water in the trunk for automatically closing said opening, and means whereby said opening and closing means may be selectively operated at will. 90

11. A ventilator comprising a primary trunk open at the upper end, an automatic trunk-clearing element at the lower end, a ventilating opening in the trunk between the upper open end and the automatic trunk clearing opening, and means for closing said opening against the admission of water, said means operating under the flotation effect of the water when the trunk is upright and operating against the flotation effect of the water when the trunk is inverted. 105

12. A ventilator comprising a primary trunk open at the upper end, an automatic trunk-clearing element at the lower end, a ventilating opening in the trunk between the upper open end and the automatic trunk clearing opening, a closure for the opening, a float for operating the closure under the flotation effect of water in the trunk when the trunk is upright, and a weight for operating the closure when the trunk is inverted. 110

In testimony whereof I have hereunto signed my name.

FRED NICHOLAS NELSON.
